UNITED STATES PATENT OFFICE.

LOUIS V. ARONSON, OF NEWARK, NEW JERSEY.

MOVING-PICTURE TOY.

Application filed October 6, 1923. Serial No. 666,973.

To all whom it may concern:

Be it known that I, LOUIS V. ARONSON, a citizen of the United States, residing at Newark, in the county of Essex and State 5 of New Jersey, have invented certain new and useful Improvements in Moving-Picture Toys, of which the following is a specification.

The invention relates to toys, and has as 10 an object the provision of a toy to produce moving pictures, which shall be cheap to manufacture and which will not readily be put out of order.

A further object of the invention is the 15 provision of a moving picture toy in which the pictures and the viewing slits shall move in opposite directions so as to secure the effect of high speed and rapidly moving parts.

20 A further object of the invention is the provision of a toy of the class described having a picture disk which is readily reversible, and interchangeable, so as to make more than one series of pictures available.

25 A further object of the invention is the provision of a moving picture toy having a form of drive which may be very cheaply produced from stampings without the need for any machining.

30 Further objects of the invention will appear from the following description when read with the accompanying drawings showing an illustrative embodiment of the device and in which—

35 Fig. 1 is a front elevation, partly broken away.

Fig. 2 is a central vertical section on line 2—2 of Fig. 1, with the crank revolved 90°.

40 Fig. 3 is a rear elevation omitting the handle and the crank.

Fig. 4 is a detail elevation of a portion of the picture disk.

45 Fig. 5 is a front elevation of the form of the invention which is at present preferred.

Fig. 6 is a rear elevation of the same with the picture disk omitted.

Fig. 7 is a detail section on broken line 50 3, 3 of Fig. 5, and

Fig. 8 is a detail section on line 8, 8 of Fig. 6.

As shown, the device comprises a disk 10, 55 preferably stamped from sheet metal, and having a handle 11 formed from the same material, bent into the form of a cylinder.

The handle may be made from separate material and attached to the disk, as will be described in connection with Figs. 5-8. To support the moving disks there is shown 60 a shaft 12 rigidly secured at a median point of its length to the disk 10.

To carry the moving viewing slits 13, there is shown a disk 14 in which the slits are formed adjacent its margin. The disk 65 14 is shown as provided with a sleeve or bushing 15 rigidly secured thereto, loosely mounted upon one end of the shaft 12, and the disk and sleeve or bushing may be revolvably secured thereto by means of a 70 screw 16. The washer 17 may be rigidly secured to the disk if preferred. Preferably circular beads 44 and 45 are pressed into the material of the disk 14 at the margin thereof, and at the inner ends of 75 the slits 13 to increase the stiffness of the disk.

To carry the picture disk there is shown a supporting disk 18 provided with a sleeve or bushing 19 revolvably mounted upon the 80 opposite end of shaft 12 and retained thereon by a screw and a washer 21. To increase the rigidity of the disk 18 there is shown an annular flange 22 formed upon its margin.

To drive the disks 14 and 18 in opposite directions there is shown a friction wheel 23 carried upon a shaft 24, mounted in loops 25 and 26, preferably formed by bending strips of material struck out from the material of the disk 10, and adapted to be driven by means of a crank 27, preferably formed by bending the material of the shaft 24.

The friction disk 23 is shown as formed 95 with a diameter slightly greater in extent than the space between the disks 14 and 18 when mounted upon the shaft 12, so that the tightening of the screws 16 and 20 will cause the aforesaid disks to press against the 100 friction disk, and therefore turning of the crank 27 will cause the disks 14 and 18 to be revolved in opposite directions.

To support a picture disk 28 removably upon the disk 18, there are shown a pair 105 of clips 29, preferably struck from the material of the disk 18 and bent to hook form. The disk 18 is shown as provided with an opening 30 adapted to be placed over each of the hooks 29, and a central opening 31 110 terminating at such a point that when the disk is slipped under the hooks 29 and the

disk impinges against the washer 21, the picture disk will be centrally placed so as to be concentric with the disk 18. A series of pictures 32 are shown upon one side 5 of the picture disk differing from each other in the well known manner to cause semblance of motion when viewed in rapid succession, and it is proposed to produce a second series of pictures upon the reverse side of 10 the disk 28, which may be viewed by reversing the disk upon its support. The disk 10 is provided with a gate 33, through which the pictures are viewed; and through the successive slits 13 moving in one direction the 15 pictures are viewed moving in the opposite direction. Preferably, the disk 10 is also provided with beads 34, 35 to increase its rigidity.

In the form of the invention shown in 20 Figs. 5, 6 and 7, the friction disk or form of the invention above described is replaced by a gear or sprocket wheel 36, which is rigidly attached to the end of the shaft 24' which, as shown in Fig. 6, may be secured 25 by means of a plurality of tongues 37 struck from the material of the supporting disk 10 and bent about the shaft. The loops for journaling the shaft 24 or 24' may, obviously, be otherwise produced and secured to 30 the disk 10 or 10'. To co-act with the teeth of the gear 36, there are shown a series 35 of perforations 38 in the viewing disk 14', and a second series of perforations 39 in the supporting disk 18'. The series of perforations 38 and 39 are produced in circles in the respective disks in such a manner that the teeth 36 will co-act therewith to cause revolution of the disks in opposite directions, providing a positive actuation of the 40 disks.

In the form of the invention shown in 45 Figs. 5, 6 and 7, the handle 11' is shown as produced from a separate piece of material and secured to the supporting disk by tabs 40, 41' which may be passed through 50 slits in the supporting disks and may be clinched upon the opposite side thereof. Obviously, the parts might be brazed or 55 electrically welded to provide the desired attachment. The wings 42, 43 upon which the tabs 40, 41 are formed are preferably formed from the same sheet of material as is the handle 11', the latter portion thereof

being bent into the form of a cylinder with the portion bearing the wings formed into 55 a half cylinder having the wing extensions in opposite directions thereon, as shown in detail in Fig. 8.

Minor changes may be made in the physical embodiment of the invention without departing from its spirit.

I claim:

1. A moving picture toy comprising, in combination, a supporting disk having a shaft rigidly secured thereto at a median point of its length, a disk revolubly mounted on one end of said shaft having a series of viewing slits therein, a second disk revolubly mounted upon the opposite end of said shaft having a series of pictures thereon, 65 a gate in said supporting disk, and means for causing said revoluble disks to rotate in opposite directions.

2. A moving picture toy comprising, in combination, a supporting disk having a gate therein, a shaft rigidly mounted upon said disk, a viewing disk rotatably mounted upon one end of said shaft having a series of viewing slits therein, a supporting disk mounted upon the opposite end of said shaft, 75 a picture disk revolubly and reversibly mounted upon said last named disk and carrying a series of pictures upon opposite sides thereof each adapted to be turned toward said viewing disk, and means for causing the revoluble disks to rotate in opposite directions.

3. A moving picture toy comprising, in combination, a supporting disk having a gate and an opening therein, a shaft mounted upon said disk, a sprocket wheel mounted upon said shaft and protruding through said opening, a shaft centrally and rigidly mounted upon said supporting disk, a viewing disk revolubly mounted upon one end of said shaft having a circular series of perforations therein coating with the teeth of such sprocket wheel, a supporting disk revolubly mounted upon the opposite end of said shaft having a circular series of perforations therein coating with the teeth upon said sprocket wheel opposite the said first mentioned teeth, whereby revolution of said shaft may cause said revoluble disks to rotate in opposite directions.

LOUIS V. ARONSON.
